MORNING GOWN

Filed Feb. 15, 1923

UNITED STATES PATENT OFFICE.

ANNIE W. STIMSON, OF LOS ANGELES, CALIFORNIA.

MORNING GOWN.

Application filed February 15, 1923. Serial No. 619,308.

This invention relates to a morning gown or dress. If a morning gown or house dress is put on by slipping it over the head, it may disarrange one's hair. The general object 5 of the invention is to produce a garment of this kind which is of simple construction but which can be put on without necessitating its being slipped over the head; also to produce a dress of this kind which can be 10 made by an unskilled seamstress, but which will present an attractive appearance such as that of a more elaborately made garment. One of my objects is to produce a dress which can be very quickly put on.

15 Further objects of the invention will appear hereinafter.

The invention consists in the novel parts and combination of parts to be described hereinafter, all of which contribute to produce 20 an efficient morning gown of the type described.

A preferred embodiment of the invention is described in the following specification while the broad scope of the invention is 25 pointed out in the appended claims.

In the drawing—

Figure 1 is a front elevation of a morning gown embodying my invention and showing the upper portion of the gown 30 thrown open.

Fig. 2 is a rear elevation of the upper portion of the gown, the lower portion being broken away.

Fig. 3 is a perspective illustrating the 35 general construction and appearance of the gown when worn.

The morning gown comprises a front body portion 1 and a front skirt portion 2. These parts are preferably made in one 40 piece, that is to say, with a "straight front" effect. The body portion has a double breasted coat-like form with a substantially square neck opening and comprises an inner flap 3 which extends across the front from one side, for example, the left side, and an outer flap 4, which extends across from the opposite side. These flaps when in position over-lap each other considerably, so that the vertical edge 5 of the outer flap lies considerably on one side of the middle line of the gown.

In this way the upper portion of the garment is divided at the front so that when the outer flap is thrown back as illustrated in 55 Figure 1 a relatively large V shaped open-

ing 6 will be formed in the front. This opening extends down to a point such as the point 7 at or about the waist-line. From this point downwardly the two flaps 3 and 4 are attached together by seam 8 which extends to the point 7 from the lower edge 9 of the gown.

The garment is provided with a neck opening 10 which is preferably of square form or keystone form.

The gown is also provided with a sash 11 which is a piece separate and distinct from the gown attached to the gown only at one point, that is to say, its middle portion is attached on a stitched line 12 extending horizontally across the flap 4 at or about the waist-line, and the body of the sash extends completely across, that is, straight across the front so that the two ends 13 of the sash may pass around to the back and be tied 75 in a bow 14 (see Figure 3).

The garment may have short sleeves 15 as illustrated.

The gown is preferably provided with a back 16 which is devoid of a central back seam and this back is attached by side seams 17 to the body portion and skirt portion of the front of the garment. These seams 17 are preferably located at the side, but somewhat toward the rear so that they cannot 85 be seen from the front, the back 16 is also provided with a substantially horizontal lower seam 18 which attaches it to a rear skirt portion 19. This rear skirt portion is also attached by side seams 20 to the skirt portion 2 of the gown and these seams 20 may be substantially in line with the aforesaid seams 17. In order to produce a fullness in the back skirt portion 19 the same may be provided with Shirring as indicated 90 at 21 in the vicinity of the horizontal seam 18.

A gown embodying these features of construction may be readily put on by throwing the flaps 3 and 4 open at the neck and stepping into it. This avoids the necessity for putting the gown over the head which might disturb the arrangement of the hair.

In order to give the gown an ornamental appearance, the edges of the neck opening 10 and the flaps 3 and 4 may be provided with a piping strip or braid 22 of a different color from the gown. Similar piping or braid 23 may be applied along the arm seams. The gown may also be provided if 110

desired with a pocket 24 and if desired ornamental embroidery may be placed at 25 on the flap 4 and also on the pocket.

The flap 4 is of course detachable from the 5 flap 3 at will and for this purpose fastening means is provided preferably consisting of a snap button 26 near the edge of the flap 3 and a button 27 and button-hole 28 located near the edge 5 of the outer flap.

10 The outer flap over-laps the inner flap considerably so that no other fastenings are necessary.

While the gown presents a very ornamental appearance, it can be very quickly 15 put on without disturbing the hair and the act of dressing is completed after the dress is put on simply by attaching the two fastening devices and tying the sash.

It is understood that the embodiment of 20 the invention described herein is only one of the many embodiments this invention may take and I do not wish to be limited in the practice of my invention nor in my claims to the particular embodiment set forth.

25 What I claim is:—

1. A morning gown having an opening extending down the front with an inner flap at the front and an outer flap extending across the front to a point at the side and 30 overlapping the inner flap, with means for

detachably connecting said flaps together at the neck of the gown, and a sash in the form of a band attached at about its middle point to the front of the garment substantially at the waist line and passing substantially straight across the front and around to the back of the gown, and means permanently attaching the flaps together below the said sash. 35

2. A morning gown having a front opening extending from the neck down below the waist line, and having an inner flap at the front with an outer flap extending across the front so that its vertical edge is near one side of the garment and overlaps the 45 inner flap, means for detachably connecting said flaps together at the neck of the gown, and a sash located above the lower end of the front opening attached at about its middle point to the outer flap at the front of 50 the garment substantially at the waist line, said sash consisting of a band passing substantially straight across the front and around to the back of the gown, and means permanently connecting the flaps together 55 below the sash.

Signed at Los Angeles, California this 6th day of February, 1923.

ANNIE W. STIMSON.
